UNITED STATES PATENT OFFICE.

ALLAN RAMSEY, OF EVANSTON, ILLINOIS, ASSIGNOR TO SCHWEITZER & CONRAD, OF CHICAGO, ILLINOIS, A CORPORATION OF ILLINOIS.

HIGH-TENSION SWITCH.

Application filed February 18, 1924. Serial No. 693,620.

My invention relates to switches and more particularly to high tension switches.

It is a purpose of my invention to provide a high tension switch that is provided with a movable contact means, said movable contact means comprising a minimum number of movable parts. Preferably, only the switch blade moves, thus reducing the number of movable parts and the weight thereof. This is highly important as in a high tension switch with large, heavy parts, the number of such parts that move determine largely the difficulty of operation of the switch, as any increase in the number thereof increases the weight that has to be moved materially. By providing a switch comprising a mechanism in which the blade only moves the weight of the moving parts is reduced to a minimum.

Preferably, the movable switch blade is mounted on an insulated support and is moved by means of a revolving insulator, said insulator being driven by suitable mechanism from a remote point. Preferably, the switch blade is driven by a rack and pinion, the pinion being driven through the revolving insulator. Said movable contact preferably co-operates with a fixed contact or contacts with which the movable

blade has sliding engagement.

It is a further purpose of my invention to provide a switch mechanism of the above mentioned character which can be constructed in the form of either a single or double throw switch. The operating mechanism and the driving mechanism for the blade and the mounting of the blade are substantially the same for a single and double throw switch, thus making it possible to use a standardized construction with either form, the only important difference between the two switches being that in the case of the double throw switch the movable blade is mounted intermediate two stationary contacts, whereas in the case of the single throw switch a stationary contact member is provided only at one side of the movable contact means, said stationary contact or contacts being aligned with the movable contact so that the movable contact or switch blade moves into engagement with the stationary contact or contacts by a longitudinally sliding movement.

It is still a further purpose of the invention to provide said fixed or stationary con-

tacts with self-aligning contact means, said contact means being resiliently mounted in such a manner as to provide substantially a universal mounting of the contact means, said stationary contact preferably comprising a weatherproof casing within which said resiliently mounted contact members are housed.

It is still a further purpose of the invention to provide stop mechanism for preventing the movable contact means from moving too far into the stationary contact means to thus avoid any damage due to the movement of the movable contact means beyond its normal engaging position with the stationary contact means. The mechanism for operating the switch comprises gearing that has such a ratio that a comparatively large movement of the switch blade occurs with each revolution of the driving shaft of said operating means, thus causing a rapid movement of the switch blade into and out of circuit closing position. It is obvious that, due to the rapid movement of the blade, it would be easy to move the blade too far if no suitable mechanism were provided to prevent this movement, thus causing considerable damage to the stationary contact mechanism.

It has been found that it is most desirable to provide a positive stop for the movable blade so as to avoid any damage to the stationary contact means. Said stop is preferably provided on the driving shaft near the driving mechanism which, in the forms shown in the drawings, is a hand wheel driving the shaft through a worm wheel and worm and comprises a screw thread or worm having a nut mounted thereon, said nut being provided with stop mechanism co-operating with stationary stop means to limit the movement thereof in both directions. The nut is so mounted as to be held against rotation, thus moving lengthwise of the threaded member as the same is rotated and upon engagement with the stop means stopping the rotation of said threaded or worm member.

Other objects and advantages of the invention will appear as the description of the accompanying drawings proceeds. However, I desire to have it distinctly understood that I do not intend to limit myself to the exact details shown or described but that I intend to include as part of my inven-

tion all such obvious changes and modifications of parts as would occur to a person skilled in this art and as would fall within the scope of the claims:

5. In the drawings:

Fig. 1 is an elevation, partly broken away, of my improved switch mechanism, showing the arrangement thereof when used as a single throw switch;

10 Fig. 2 is a side view in elevation of said switch mechanism with a portion of the operating mechanism omitted, said view being taken at right angles to Fig. 1;

15 Fig. 3 is a plan view of the devices shown in Fig. 2;

Fig. 4 is a plan view of the switch blade used in the form shown in Figs. 1 to 3 inclusive;

20 Fig. 5 is an enlarged plan view, partly broken away, of the movable contact member supporting means shown in Figs. 1 to 3 inclusive;

25 Fig. 6 is a view in side elevation of said means taken substantially from the line 6—6 of Fig. 5, showing the switch blade in position therein;

Fig. 7 is a section taken on the line 7—7 of Fig. 5;

30 Fig. 8 is an enlarged view, partly in vertical section and partly in elevation, of the rotatable insulator and the driving mechanism for the movable switch blade cooperating therewith;

35 Fig. 9 is a view in vertical section and partly in elevation of the driving connection between the vertical and horizontal driving shafts of the switch actuating mechanism;

40 Fig. 10 is a plan view of the driving means for said actuating mechanism when a hand wheel is employed, said view being taken with the cover of the housing for said driving means removed and the driving shaft being shown in section;

45 Fig. 11 is a view in side elevation of the stationary contact means;

Fig. 12 is an end view thereof;

Fig. 13 is a section thereof taken on the line 13—13 of Fig. 11;

50 Fig. 14 is a view, partly in vertical section and partly in elevation, of the stop mechanism on the actuating means to limit the movement of the movable switch blade and adjoining portions of the actuating mechanism;

55 Fig. 15 is a section thereof taken on the line 15—15 of Fig. 14;

Fig. 16 is a face view of the stop mechanism housing;

60 Fig. 17 is a view similar to Fig. 1 of a double throw high tension switch mechanism;

Fig. 18 is a view similar to Fig. 2 of a double throw high tension switch mechanism;

65 Fig. 19 is a plan view of the switch blade

used in the double throw switch mechanism; and

Fig. 20 is a fragmentary face view of the stop mechanism housing for a double throw switch mechanism.

Referring in detail to the drawings, the switch mechanism shown in Figs. 1 to 16 inclusive is mounted on any suitable support comprising a vertical member 10 and horizontally extending frame members 11. Said frame members 11 may be made in any desired manner, preferably being built up of structural members.

Mounted on the vertically extending supporting member 10 is a suitable bracket 80 member 12 provided with a boxlike housing 13 into which extends the stub shaft 14 which is connected with the vertically extending shaft 15 by means of any suitable coupling member 16. In the housing 13, mounted on the shaft 14, is a beveled gear 17 which meshes with the gear 18 provided on the horizontally extending shaft 19. The shafts 14 and 19 are journaled in the housing and in the central bearing member 20, as shown in Fig. 9.

The frame work members 11 are provided with suitable brackets 21 which are provided with a housing 22 having the bearings 23 and 24 for the horizontally extending shaft 25, said shaft 25 being connected with the shaft 19 by means of the shaft or tube 26 through the couplings 27 and 28. In the form shown in Fig. 1 three parallel frame members 11 are provided and three brackets 21 are shown, each of the brackets having a shaft portion 25 projecting therefrom. The shaft 25 also extends outwardly from the housing 22 beyond the bearing 24 and each such shaft portion 25 is connected with the shaft 25 projecting from the adjoining housing 22 by means of a suitable piece of shafting or tubing 29 by means of couplings 30 and 31 similar to the couplings 27 and 28.

Mounted on the shaft 25 in each of said housings 22 is a beveled gear 32 which meshes with a beveled gear 33 provided on the vertically extending shaft 34 extending through a bearing 35 in the top of the housing 22. The details of this structure are shown in Fig. 8. The upper end of the shaft 34 has mounted thereon a flanged coupling member 36 so as to rotate with said shaft 34. Bolted to said coupling member 36 by means of the bolts 37 is a flanged member 38 which has a stem portion 39 that is rigidly mounted in the insulator 40 so that said insulator 40 will rotate with the shaft 34 and the member 38.

Each of the members 11 is also provided with a bracket 41 to which is bolted a flanged base member 42 provided on the insulator 43. Said insulator 43 has bolted thereto at the top thereof a bracket 44, said bracket 44 being shown more in detail in Fig. 8. 130

The bracket 44 is provided with a housing 45 which is provided with bearing portions 46 and 47 for a vertically extending stub shaft 48 which has the flanged member 49 keyed thereto, said member 49 being secured to the insulator 40 by means of the bolts 50. Mounted on said shaft 48 is a beveled gear 51 that meshes with a beveled gear 52 provided on the horizontally extending shaft 53 which is journaled in the bearing portion 54 provided on the bracket 44. Said shaft 53 is provided with a pinion 55 which meshes with the rack 56 provided on the movable contact member 57, the construction 15 of these parts being clear from Figs. 5 and 6, from which it will be evident that the bracket 44 is provided with a flanged portion 58 for securing the same to the insulator 43 and with a central housing comprising the longitudinally extending members 59, which housing is provided with a cover 60. The bracket member 44 is made in two parts which are secured together by means of the bolts 61 and 62 passing through the 25 longitudinally extending members 59. The longitudinally extending members 59 are also provided with threaded hollow studs 63 into the sockets of which the coil springs 64 extend, whereby the tension of said 30 springs may be adjusted, said springs 64 having shoes 65 mounted on the inner ends thereof, said shoes being provided with end portions 66 curved in a direction away from each other. Flexible conductors 150 are secured to the shoes 65 by means of the bolts 151 and to the bottom 152 of the casing by the bolts 153. The shoes 65 engage with the movable contact member 57, guiding the same and providing an electrical connection 40 between the stationary terminal 109 and the movable contact member. The member 57 is guided in its movements by the rollers 160 and 161. The rollers 161 have central flanges 162 extending between the members 15 73 and 68 to hold the member 57 in axial alignment.

Referring to Fig. 4, it will be seen that the movable contact member comprises a central body member 67 upon which the rack 56 is provided and an outer member 68 of material of high conductivity on each side of the member 67, the members 68 being off-set as shown at 69 and being brought into face to face relationship beyond the end of the member 67, as indicated at 70, and being further beveled at the ends thereof as shown at 71. Mounted between the members 68 and the body member 67 at the point of said contact member 57 that engages with the shoes 65 are the filler members 72. Said members 72 terminate substantially with the end of the member 67 shown at the right of Fig. 4 and said members 68 extend slightly beyond said end and are brought together 45 as shown at 73. It will be noted that the

members 72 and 68 are wider than the member 67 thus holding the rack and pinion in alignment.

It will be evident from the above that when the shaft 15 is rotated the shaft portions 25 will be rotated through the gearing in the housing 13 and all the insulators 40 will be rotated through the gearing in the housings 22. As said insulators 40 rotate the shafts 53 will be rotated through the 70 gearing in the housing 45 and the pinion 55 engaging with the rack 56 will cause said rack and the movable contact member 57, upon which the same is mounted, to be moved lengthwise with the shoes 65 always in engagement with the outer faces thereof. Each of said members 57, in the form shown in Figs. 1 to 16 inclusive, co-operates with a stationary contact member to complete a 80 circuit by longitudinal or axial movement of 85 said movable contact member.

It will be evident that, due to the arrangement of the stationary insulator 43 for supporting the bracket 44 and the upper bearing for the insulator 40, a very sturdy construction is provided and all movable parts, except the switch blade itself, are rotating parts that are journaled in bearings as is common practice in machinery, thus providing a device in which all of the movable parts are easily operable and are under no unnecessary strain as is often the case with long, swinging arms or long, heavy, lengthwise movable members.

Each of the members 11 is provided also with a flanged base member 74 upon which the insulator 75 is mounted. The insulator 75 has mounted on the upper end thereof a stationary contact 76. Said stationary contact is shown more in detail in Figs. 11 to 13 inclusive and comprises a housing made up of the members 77 and 78, said members being provided with rearwardly extending ears 79 and 80 together, forming a terminal for a conductor, suitable openings 100 110 being provided for fastening devices for securing the conductor thereto. The member 78 is provided with flanges 82 which are provided with elongated slots 83 which are slightly arcuate, as will be seen, and are 115 curved on a common center. Said slots 83 are provided for the securing members for clamping the contact member 76 on the insulator 75, thus permitting of adjustment of the housing so as to align the same properly 120 with the movable switch blade 57. The contact member 76 is provided with side wall portions comprising portions 84 converging toward the open end of said housing, wall portions 85 converging toward the rear of 125 said housing and wall portions 86 converging slightly toward the rear of said housing. Rearwardly of said portions 86 is the vertically extending portion 87 of the housing which is made in the form of a block to 130

which the flexible braided wire ribbon member 88 is clamped by means of the beveled clamping members 89 held in clamping relationship thereto by means of the bolts 90. 5 The flexible member 88 has a portion 92 extending around the rear side of the block 87 and forwardly extending portions 93 upon which the contact shoes 94 are mounted. The contact shoes 94 extend in substantially 10 parallel relationship and are provided with diverging outer ends 95, said member 88 lying adjacent thereto and being secured to the portions 95 by means of the screws 97. Thus, the member 88 acts to conduct the 15 current from the shoes to the housing of the contact 76. Clamped between the members 87 and 89 are also the spring members 98, 99 and 100, said members being of graduating length, the member 98 being the longest and the other members being gradually shorter so as to provide a spring mechanism of gradually increasing flexibility toward the forward end of the housing. The contact shoes 94 are provided with securing 20 members 101 for securing the flexible member 88 thereto, the springs 98 being also received over said securing members and being held thereon by means of the cotter pins 102 but having a slight movement on said 25 securing members. The members 94 are further provided with studs 103 which pass through the members 88 and 98 and serve as guide members therefor to hold the same in alignment.

30 As will be clear from Figs. 2 and 3, the switch blade 57 enters the housing made up of the members 77 and 78. Said movable contact member 57 enters between the shoes 94 having the outwardly deflected ends 95, and it will be evident from Fig. 12 that said 35 shoes are arranged in pairs and that any desired number may be used depending upon the capacity of the switch, three pairs being shown in Fig. 12. The open end of the 40 housing of the stationary contact member 76 is provided with outwardly flared wall portions 105 which gradually curve from the edge portions thereof toward the interior of the housing so as to act as guide 45 means for the movable contact member to direct the same into engagement with the contact shoes of the stationary contact member. The stationary contact member is further provided with a pair of guide members 50 106 on opposite sides thereof which are curved as shown in Figs. 12 and 13 so as to form converging guides for directing the movable contact member into proper relationship with the shoes of the stationary 55 contact.

60 It will be seen that due to the mounting of the contact shoes the same will lie substantially in parallelism and will be resiliently urged toward each other so that the 65 movable contact will slidingly engage with

the said contact shoes so as to form a good electrical connection therewith, and further, that the shoes mounted on the stationary contact member will always be in proper alignment to co-operate with the movable 70 contact member or switch blade, this being due to the flexible mounting thereof. The members 77 and 78 are secured together in any suitable manner as by means of the bolts 107 and 108, bolt 107 passing through the 75 clamping block 87 against which the spring members are held by means of the members 89.

76 From the foregoing it will be seen that when the shaft 15 is rotated and the insulator 40 is rotated thereby in one direction, the movable switch blade 57 will move into engagement with the contact shoes 94 on the movable contact 76 and complete the circuit from the terminal on the member 76 to a 80 suitable terminal on the bracket 44, said terminal being shown in Fig. 5 as being a lug 109 provided with openings 110 for receiving suitable securing means for clamping a conductor thereto.

85 It will be further noted that the contact elements provided in the stationary contact 45 76 are so housed as to be entirely protected from the weather, thus preventing moisture from interfering with the proper operation of said contacts or preventing any other means from interfering with the proper operation thereof. It will also be noted that the shoes 65 provided for engagement by the 90 movable contact member on the bracket 44 are housed by the cover 60, said cover being provided with downturned lips 111 on the ends thereof to more completely enclose the ends of the housing through which the 95 movable switch member 57 projects.

100 The shaft 15 may be driven by any suitable means, either by power or by hand. In the arrangement shown in the drawings, the shaft is driven by hand through the hand wheel 112 which is mounted on a shaft 113 which projects from the housing 114 which is mounted on a suitable bracket 115 on the support 10. The shaft 113 is provided with a worm 116 which meshes with a worm wheel 117 which is keyed on the shaft 118 projecting out of the top of the housing 114. The shaft 118 is coupled to a shaft 119 projecting from the housing 120 by means of a coupling 121. The housing 120 contains a suitable stop mechanism for limiting the 115 movement of the shaft 118 and the shaft 15 in either direction. The shaft 119 extends through the housing 120 and is connected with the shaft 15 by means of a flexible coupling 122. The housing 120 is 120 mounted on the support 10 in any suitable manner, as by means of the bolts 123.

125 It will be noted, upon reference to Figs. 14, 15 and 16, that the shaft 119 is provided with a thread 124 thereon upon which 130

is mounted an interiorly threaded nut 125 and that said nut 125 is square and fits within the housing 120 so that the same will not rotate on the shaft 124 but will be held 5 against rotation due to the same being confined by the walls of the housing 120. Accordingly, the nut 125 will move up as the shaft 119 is rotated in one direction and down as it is moved in the other direction. 10 the shaft being held from axial movement relative to the housing by means of the collars 126 and 127 provided therein. Said collars 126 and 127 co-operate with the nut 125 to serve as stop members for limiting 15 the rotation of the shaft 119, and consequently the shaft 15 and the hand wheel 112, in either direction to thus prevent the switch blade 57 from being moved too far either into open circuit position or closed 20 circuit position in co-operative relationship with the stationary contact 76. It is necessary that a positive stop absolutely limiting the rotation of the shaft 15 at a predetermined point be provided, as the switch blade 25 57 moves a considerable distance every time the shaft 15 is rotated. Thus, if a positive stop were not provided the switch blade might enter too far into the stationary contact member 76 and damage the same. 30 It will be noted that the ends of the nut 125 are not plane but are inclined, there being two inclined portions 128 provided on one end of the nut and two inclined faces 129 provided on the other end of the nut. 35 The inclined faces 128 terminate in shoulders 130 and the inclined faces 129 terminate in shoulders 131. The nut 126 is also provided with inclined faces 132 defining shoulders 133 with which the shoulders 130 engage 40 when the nut 125 is moved upwardly as far as it can go, thus positively stopping the movement of the nut 125 and consequently positively stopping the rotation of the shaft 119 and the shaft 15. In the arrangement 45 shown in the drawings, when the member 125 is in engagement with the stop 126 and the shoulders 133 and 130 are in engagement the limit of the opening movement of the switch is reached. 50 The stop member 127 is provided with inclined faces 134 defining shoulders 135 with which the shoulders 131 on the nut 125 engage when the nut 125 is moved to the limit of its movement downwardly, thus limiting 55 rotation of the shaft 119 and shaft 15 in the opposite direction or limiting the movement of the movable contact 57 into the stationary contact 76.

The housing 120 is provided with an opening 136 having a window 137 provided therein so that the interior of the housing can be seen therethrough. The nut 125 is preferably provided with suitable markings, such as the stripes 138 and 139 thereon, and 60 the glass 137 is provided with a stripe 140

thereon. The stripes 138, 139 and 140 are provided as signal means to the operator to indicate when the nut 125 is approaching the limit of its movement in either direction. When the stripe 138 is substantially aligned with the stripe 140 the nut will be in its downward limiting position and when the stripe 139 is in substantial alignment with the stripe 140 the nut will be in its upward limiting position. 70

In Figs. 17 to 20 inclusive, a double throw switch is shown which is very similar in construction to the single throw switch shown in Figs. 1 to 16 inclusive.

In the form shown in Figs. 17 to 20 inclusive, the vertically extending shaft 15' may be driven by any suitable means such as by a power operated device or by means of the hand wheel 112' which drives the shaft 15' through the gearing provided on the housing 114', which is the same in construction as that shown in Figs. 1 to 16 inclusive, provided in the housing 114, through the stop mechanism provided in the housing 120', said shaft 15' driving the horizontally extending shaft 19' through the gearing provided in the box 13' in a similar manner to which the shaft 19 is driven from the shaft 15. Said shaft 19' is connected with the shaft portions 25' through the shaft portions 26' and 29' which are connected together by means of suitable couplings in the same manner as the shafts 26 and 29 connect the shaft portions 25 in Fig. 1. 95

While it is evident that either the double 100 or single throw switch may be made so that the insulators extend either above or below the horizontal drive shaft. In the drawings the single throw switch is shown with the insulators above the drive shaft and the double throw switch with the insulators below the drive shaft. 105

Referring again to Fig. 17, it will be seen that the horizontally extending framework members 11' are provided upon which the brackets 21' and 41' are provided. The brackets 21' are provided with housings 22' provided with suitable gearing therein, similar to that provided in the housing 22, for driving the rotatable insulators 40', and the 110 brackets 41' have secured thereto the stationary insulators 43' from which the bracket members 44' depend, said bracket members 44' corresponding to the brackets 44 in Figs. 1 to 16 inclusive, and being provided with suitable housings 45' within which suitable driving mechanism is provided for operating the movable contact member 57' through a rack and pinion, in a similar manner to that in which the member 57 is driven from the 115 rotatable insulator 40. 120

Contact is made between the stationary parts of the housing 44' and the movable contact 57' by means of suitable shoes corresponding to the shoes 65 shown in Fig. 5 125 130

and from said shoes the circuit leads to the ends thereof out of contact with the stationary contact members and at a substantial distance therefrom so as to provide an open circuit between the terminal 109' and both terminals 141 and 142. It will be evident that the stop members provided in the housing 120' will prevent excessive movement of the movable contact 57' into the stationary contact member 76' when the nut 125' reaches the limit of its movement in one direction and into the contact 76'' when the nut reaches the limit of its movement in the opposite direction. 75

Having thus described my invention, what I desire to claim and secure by United States Letters Patent is:

1. In a switch of the character described, a supporting framework, a stationary contact member insulatingly mounted thereon, a pair of insulators mounted on said framework, a bracket mounted on one of said pair of insulators provided with a housing, contact means in said housing, the other of said insulators being mounted for rotation on said bracket, a movable contact element having sliding engagement with the contact means in said housing, and a driving connection between said contact element and said rotatable insulator whereby said element is moved toward or away from said stationary contact when said insulator is rotated, said housing being open at opposite ends thereof, whereby said contact element is projected from one end of said housing when said insulator is rotated in one direction and from the other end of said housing when rotated in the other direction. 80
  2. In a switch of the character described, a support, a housing on said support, an axially movable contact element mounted on said support in said housing, a pair of stationary contact members on opposite sides thereof and means for projecting said contact element in either direction from said housing to close the circuit through either of said pair of contact members. 100
  3. In a switch of the character described, a movable contact element and a stationary contact member adapted to receive said element, said stationary contact comprising a pair of contact shoes engaging said element, a flexible conducting member upon which said shoes are mounted and graduated elongated resilient means supporting said shoes at the free end thereof and urging the same toward said element, said shoes being adjustable relative to said resilient means. 110
- In witness whereof, I hereunto subscribe my name this twenty-eighth day of January A. D., 1924. 120

ALLAN RAMSEY.
